(57) **CLAIM**

The ornamental design for a bicycle clipless pedal platform adapter, as shown.

DESCRIPTION

FIG. 1 is a top plan view of a bicycle clipless pedal platform adapter embodying our design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a bottom plan view thereof; and,

FIG. 7 is a top perspective view thereof.
